UNITED STATES PATENT OFFICE.

ADOLF HOFFMANN, OF CONSTANCE, GERMANY.

DEVICE FOR MOISTENING AND APPLYING GUMMED PAPER.

SPECIFICATION forming part of Letters Patent No. 691,379, dated January 21, 1902.

Application filed September 5, 1901. Serial No. 74,406. (No model.)

To all whom it may concern:

Be it known that I, ADOLF HOFFMANN, a subject of the Grand Duke of Baden, residing at 4^a Schulstrasse, Constance, in the Grand 5 Duchy of Baden and Empire of Germany, have invented a new and useful Device for Moistening and Applying Gummed Paper, of which the following is a specification.

It is a well-known fact that exactly-fitting 10 clothes have hitherto been made only by expert cutters employing very difficult calculations and repeatedly trying on such clothes, and even then misfits have occasionally been the result. By my said invention, which has 15 for its object to obviate this drawback, I am enabled to produce in a few minutes a covering which resembles a cast of the body to be clothed and is adapted to be folded.

In the annexed drawings this invention is 20 represented.

Figure 1 illustrates a side elevation of the modeling apparatus. Fig. 2 shows a zigzag band, and Fig. 3 a metal strip formed with dents.

25 The apparatus comprises an elongated sheet metal casing which can be opened laterally. In this casing is placed a roll *a*, of paper or fabric, made, say, about three or four inches wide and gummed on one side. The paper 30 or fabric runs over a damping-roller *b* and on passing from the casing is pressed by a roller or other brush *c* upon the body. The damping-roller consists of sheet metal and is adapted to be filled with water. Below its 35 surface, covered with linen, I place a sponge, which is cut even and which draws the water through small apertures in the roller, so that the surface will always be uniformly damp. A roll *d* forces the paper or fabric upon the 40 damping-roller by means of a spring *e*, the

tension of which may be regulated by a screw *f*, Fig. 1.

If it is desired to form a covering to be used for making a coat, a chemise of gauze or soft paper is put on over the waistcoat. Upon 45 the chemise the damped adhesive strip is then wound with the aid of the modeling apparatus, Fig. 1, thereby producing a firm crust, which forms an exact copy or cast of the body. This covering is then cut open at 50 the back and removed. The covering may be cut into any desired number of parts, which serve as patterns. Ultimately the parts are joined again by means of zigzag bands *g*, Fig. 2, to reconstitute the model previously produced, which is then stiffened by metal strips *h*, punched with dents *i*, Fig. 3. Upon this model, which is placed upon an adjustable stand, any faults and irregularities may be 55 rectified.

60 What I claim as my invention, and desire to secure by Letters Patent, is—

A device for moistening and applying gummed paper comprising a sheet-metal casing, a damping-roller over which the gummed 65 or adhesive strip passes, a roller placed under the action of a spring and pressing the strip against the damping-roller, and a brush below which said strip is conducted for winding and pasting the same around the body 70 covered with soft paper or gauze, substantially as set forth.

In testimony whereof I have signed my name to this specification in the presence of two subscribing witnesses.

ADOLF HOFFMANN.
